UNITED STATES PATENT OFFICE.

DAVID M. HARKRADER, OF PITTSFIELD, ILLINOIS.

DRAFT-EQUALIZER.

SPECIFICATION forming part of Letters Patent No. 252,212, dated January 10, 1882.

Application filed November 12, 1881. (Model.)

To all whom it may concern:

Be it known that I, DAVID M. HARKRADER, a citizen of the United States, resident of Pittsfield, in the county of Pike and State of Illinois, have invented a new and valuable Improvement 5 in Draft-Equalizers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan or top view of my improved equalizer, and Fig. 2 is a front view of the same.

This invention has relation to draft-equalizers; and it consists in the construction and novel arrangement of the raised eye at the inner end of the equalizing-bar and the oblique 20 outer end of said bar carrying the single-tree attachment, and designed to provide for a lifting pull, and thereby to avoid downward pressure, all as hereinafter set forth.

In the annexed drawings, the letter A designates the double-tree, to the ends of which the equalizing-bars B are pivoted by means of the bolts C, said equalizing-bars resting on wear-plates D usually, and being arranged on the top of the double-tree. Two or more bolt-holes, 25 a, may be provided at each end of the double-tree, as indicated in the drawings. The equalizing-bars B are made of bar-iron in flattened form, and are provided in their middle portions each with two or more pivot-holes, b, cor- 30 responding in position to the bolt-holes a in the double-tree, and so arranged in order that the pivot-bolt may be shifted to adjust the draft without altering the position of the equalizing-bars. At its inner end each equalizing- 35 bar is provided with a raised eye, c, to which the single-tree hook d is designed to be attached. This eye is arranged above the equalizing-bar in order to prevent the single-trees from locking. The eye is usually fastened by 40 means of its shank e within the upwardly- curved end g of the bar, which is firmly clamped on said shank in such a manner as to hold the

eye in a fixed position with relation to the bar. The outer end, E, of the evener or equalizing-bar B is somewhat oblique with relation to the body of the bar, being inclined forward and downward beyond the twist h in the bar. A series of perforations, k, is made in the inclined end E, affording means for connecting the adjustable single-tree hook l thereto. This hook 55 is provided with a threaded shank or bolt connection, whereby it is fastened firmly to the end E of the bar, so that when the draft is applied this end of the bar will be subject to a lifting strain, tending to throw the double-tree 60 upward and to prevent downward pressure.

A double tree formed with two sets of holes and eveners connected with the double-tree by clevises and bolts, the latter being passed through the clevises and the holes in the eveners and double-tree, may be seen in my Patent 65 No. 231,037, August 10, 1880, and said construction is not claimed herein.

Having described this invention, what I claim, and desire to secure by Letters Patent, 70 is—

1. An equalizing-bar, B, having the twist h and the inclined end E beyond the twist, provided with the hook l, substantially as specified.

2. An equalizing-bar, B, having at its outer portion the inclined end E, perforated for the hook-connection, and at its inner end the raised eye c above the plane of the bar, substantially as specified.

3. The combination, with the double-tree having the bolt-holes a a in each end, of the equalizing-bars B B, having raised eyes c at their inner ends, outer inclined ends, E, hooks l, and pivot-holes b b, corresponding in position to said bolt-holes, and the adjustable pivot-bolts C, substantially as specified.

In testimony that I claim the above I have hereunto subscribed my name in the presence of two witnesses.

DAVID M. HARKRADER.
